UNITED STATES PATENT OFFICE.

ORRELL ASHTON, OF LAWRENCE, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING UPON THE TOE PORTIONS OF BOOTS OR SHOES.

No. 891,130.

Specification of Letters Patent.

Patented June 16, 1908.

Application filed June 26, 1905. Serial No. 267,074.

To all whom it may concern:

Be it known that I, ORRELL ASHTON, a citizen of the United States, residing at Lawrence, in the county of Essex and Commonwealth of Massachusetts, have invented certain Improvements in Machines for Operating upon the Toe Portions of Boots or Shoes, of which the following description, in connection with the accompanying drawings, is a specification, like reference characters on the drawings indicating like parts in the several figures.

This invention relates to machines for operating upon the toe portion of a boot or shoe after lasting, to place that part of the shoe in proper condition for subsequent operations.

Heretofore, it has been customary to trim off by hand projecting edges of the upper and lining at the toe after the shoe has been lasted. Occasion for this operation has arisen more particularly from the desirability of bringing the outersole into close and even relation to the upper and innersole, and from the necessity of preventing these projecting edges from interfering with sewing mechanism employed subsequently to lasting.

It is the object of my invention to construct a practically effective machine capable of performing this operation rapidly and economically. To this end I employ, in a machine embodying my invention, a tool for separating from the toe part of a shoe the surplus material to be removed, and means for controlling the position of the shoe while being presented to and acted upon by the tool. This means is preferably so constructed and arranged that a shoe may be quickly and accurately brought into position to be operated upon. I prefer to use a continuously actuated tool, and preferably the tool and positioning means are relatively movable so that the relation of the shoe to the positioning means need not be changed while the tool is acting. It is desirable that the relative movement be such that the shoe may be presented to the positioning means while without the path of the tool. The arrangement is preferably such that the surplus stock to be removed is brought gradually into the path of the tool, and in an acting movement of a portion of the tool but a small section of stock is removed.

In the construction shown, which forms

the preferred embodiment of the invention, I have provided a gage movable beneath a rotary cutter in a plane parallel to the axis of the cutter. The gage is shaped to receive the toe part of a shoe and is arranged to permit the projections on said toe part to extend above the upper surface of the gage. A rest is provided adjacent to the acting part of the gage to receive the toe tip. In the movement of the gage beneath the cutter, the projections on the toe part are brought into the path of the cutter and are trimmed off evenly. The shoe is held by the operator against the rest and gage and is moved forwardly with them into operative relation to the cutter, the rest and gage being returned by means tending to keep them in their initial position.

Other features of the invention will be hereinafter described.

In the drawings Figure 1 is a view in front elevation of a machine forming one embodiment of my invention; Fig. 2 is a plan view of said machine; Fig. 3 is a view in side elevation of the same; Fig. 4 is a detail view of a portion; Figs. 5 and 6 show the toe part of a shoe before and after being operated upon, respectively.

In the machine herein illustrated, which constitutes the preferred embodiment of the invention, a rotary cylindrical cutter 1 is secured to a shaft 2 suitably journaled in standards 4 and 5 carried by a base, which may be provided with any convenient means for being secured to a support. Pulleys 8 and 10, loose and fixed, respectively, on shaft 2, are arranged between the standards 4 and 5, and together with the belt shipper 12 serve as a convenient means for actuating the cutter 1.

A frame 14 is arranged below the cutter 1. The frame 14 is pivoted at its rear end upon bearings 16 carried by a bracket 18 projecting from the standard 4. The forward end of the frame is clamped in fixed position by a bolt 20 passing through a slot in the frame and entering the standard 4. A set screw 22 vertically adjustable in the forward end of the frame 14, and arranged to bear upon a lug on the standard 4, serves to permit the frame 14 to be accurately adjusted with reference to the cutter 1.

The frame 14 is provided with guideways constructed to support a plate 24 and permit said plate to be moved back and forth be-

neath the cutter 1 in an approximately horizontal path. As shown the plate 24 is provided with grooves in its side edges and strips 26 are removably secured to the top face of the frame 14 and arranged in said grooves. The forward end of the plate 24 is provided with a recess 27, as shown in Fig. 4. A gage is mounted upon the upper face of the plate 24, having its acting part, against which the toe part of the shoe to be trimmed is held, located above the recess 27. This gage comprises two sections 28, forming between them a recess of the shape of the toe of a shoe, and relatively adjustable to vary the size of the recess. If desired the gage may be made in one piece and be removably secured in position so that in case a change in width of the recess be required a different gage may be substituted.

29 A toe rest 30 is secured to the lower face of plate 24 by screws 32 passing through slots in the toe rest, said slots permitting adjustment of the toe rest longitudinally of said plate. The acting face of the toe rest inclines rearwardly, and is somewhat concave in horizontal section.

30 A spring 34 is arranged to hold the plate 24 towards the front of the machine, this spring being connected to a projection 36 on the plate 24, and to a lug 38 on the frame 14. A stop 40 is removably secured in the plate 24, and enters a slot 42 in the frame 14 to limit movement of the plate 24.

35 The gage sections 28 are secured to arms 44 pivoted at 46 upon the lower face of the plate 24. Apertures 47 in the plate 24 permit movement of the sections 28 and arms 44 upon the plate 24. A spring 48 arranged between said arms 44 tends to move the gage 40 sections apart, and a stop 50 arranged between the rear ends of said arms limits separating movement of the gage sections. The stop 50 is rotatably supported upon the plate 24 and is provided with faces arranged at 45 different distances from its axis, the construction being such that the effective width of the stop 50 may be adjusted by rotating the stop to bring different faces into contact with the arms 44, said arms being maintained in engagement with said stop by the 50 spring 48.

55 A guard 52 is illustrated supported upon the standard 4 and arranged over the cutter to prevent accidental contact with the cutter.

60 A pin 54 is shown slidably mounted in the standard 5, said pin being arranged to enter a hole in the pulley 10 to lock said pulley and shaft 2 from rotation when it is desired to re-

65 move the cutter 1.

The movement of the acting part of the cutter is preferably towards the wheel. With this movement of the cutter the trimmed ends on the upper are smoothed down in the direction of the heel and caused to lie flat on

the innersole, and any other objectionable projections on the toe part, such as lasting tacks which have been improperly inserted, are inclined towards the heel. A further advantage of this feature is that the action of the cutter tends to draw the upper tightly over the toe tip and to remove wrinkles or bunches in the upper at this point. It will be seen that the repeated strokes to which the toe part is subjected in the gradual removal of surplus stock have a considerable tendency to smooth and draw the upper towards the heel.

I regard the arrangement by which the projecting portions are gradually brought into the path of the cutter and removed by a repeated action of the cutter as of importance apart from the direction of movement of the cutter. Such an arrangement by which the projecting portions are gradually removed is advantageous in that the trimming operation is secured with less tendency to disturb the parts of the shoe adjacent to those being removed.

The upper faces of the gage sections 28 are 90 preferably arranged in a plane as near as possible to the acting edge of the cutter, so that the cutter will trim closely to said upper faces. The acting part of the gage sections is shown as beveled to a thin edge to permit the 95 path of the cutter to be in close relation to the bottom of the shoe.

In the operation of the machine shown, the operator places a shoe with its toe tip bearing against the rest 30 and the upper bearing 100 on the edge of the recess formed between the gage sections 28. It will be understood that at this stage the shoe is without the path of the cutter. The shoe is then moved with the yielding gage and rest beneath the acting 105 face of the continuously actuated cutter into operative relation to the cutter, and the projections extending above the top face of the gage sections 28 are trimmed off. The presence of lasting tacks among these projections 110 interferes in no way with the operation of the machine, as they are trimmed off with the other projections. It will be observed that the movement of the rest 30 and gage into 115 operative position is caused by pressing the toe tip against the rest. I regard this feature of importance in securing a rapid trimming operation.

The rest 30 also aids the operator in quickly bringing the part of the shoe to be trimmed into a proper position with relation to the path of the cutter. It will be seen that the contact of the toe tip with the toe 120 rest insures that the toe part of the shoe shall be introduced a sufficient distance beneath

the gage sections 28. These gage sections are adjusted to make the recess between them somewhat narrower than the toe part of the boot or shoe to be trimmed. The rest 30 may be adjusted longitudinally of the plate 24 whenever a difference in size or 125

form of the shoe to be trimmed requires such adjustment in order to bring the toe part into correct position longitudinally of the gage sections 28. It will be observed that the depth of cut of the cutter is determined by the position which is given the frame 14. By adjusting the screw 22 this position may be varied to cause the cutter to trim more or less closely to the sole of the shoe.

10 Having described my invention, what I claim as new and desire to secure by Letters Patent of the United States is:—

15 1. A machine for reducing the projecting portions of an upper upon the bottom of a shoe at the toe comprising a rotary tool for separating surplus material from the shoe and a gage formed for engagement with the bottom of the shoe and arranged to present the toe part to the tool in position to permit portions of the upper to be removed simultaneously upon opposite sides of the toe part.

20 2. In a toe trimming machine, a cutter having a fixed path, and a device formed to position the toe part of a shoe, said device being arranged for movement in the direction of the length of the shoe to permit successive portions in the length of said toe part to be moved into said path.

25 3. In a toe trimming machine, a cutter and a gage having an acting portion shaped to receive the toe portion of a shoe, and normally out of operative relation to the cutter, said gage and cutter being relatively movable to permit a toe resting against said acting portion to be brought into the path of the cutter.

30 4. A machine for trimming the projecting portions of an upper from the bottom of a shoe at the toe having in combination a cutter arranged for continuous movement, and means for guiding the toe part of a shoe into the path of said cutter arranged to maintain the innersole at said toe part in a predetermined relation to an acting face of the cutter in its movement into the path of said cutter.

35 5. A machine for trimming the projecting portions of an upper from the bottom of a shoe at the toe having in combination a rotary cutter and means for guiding the toe part of a shoe into the path of said cutter arranged to maintain the innersole at the toe part in a predetermined relation to the axis of the cutter in the movement of the shoe into the path of the cutter.

40 55 6. In a toe trimming machine, the combination with a cutter, of a gage having an acting portion shaped to receive the toe part of a shoe and to permit projections on said toe part to extend outwardly from the plane of said acting portion and arranged to maintain the shoe normally out of the path of the cutter and to move with the shoe to permit said projections to be brought within the path of the cutter.

65 7. A machine for reducing the projecting

portions of an upper upon the bottom of a shoe at the toe, having in combination, a tool for separating surplus material from the shoe arranged to be continuously actuated and a gage having an acting portion shaped to receive the toe part of a shoe, and normally out of operative relation to the tool, said gage and tool being relatively movable to permit a toe resting against said acting portion to be brought into the path of the tool. 70 75

8. In a toe trimming machine, a cutter arranged to be continuously actuated, a gage having an acting portion shaped to receive the toe part of a shoe, and a rest adjacent to said acting portion of the gage arranged to be engaged by the toe tip of the shoe, said cutter and gage and rest being relatively movable to permit a toe engaging said gage and rest to be brought into the path of the cutter. 80 85

9. The combination with gage sections, and pivotally sustained arms secured to said sections, of a stop arranged between said arms to limit relative movement of the sections in one direction, said stop having portions of its acting part of different widths and being movable to permit its effective width to be varied, and means tending to hold said arms in contact with the stop. 90

10. A machine for reducing the projecting portions of an upper upon the bottom of a shoe at the toe having in combination a tool for separating from the shoe the surplus material to be removed, means for actuating the tool, a gage shaped to receive the bottom of a shoe at the toe and to project inwardly over the edge of the shoe, and a rest adjacent to the gage arranged to be engaged by the toe tip of the shoe and to limit projection of the gage rearwardly over the edge of the shoe at the toe tip, said gage and rest being constructed to present said toe part in position to permit surplus stock to be trimmed off by the tool. 95 100 105

11. A toe trimming machine comprising a cutter, and means for positioning the bottom of a shoe at the toe in effective relation to said cutter constructed to control relative approaching movement of the cutter and said toe part and arranged to maintain the shoe normally out of the path of the cutter. 110 115

12. A machine for reducing the projecting portions of an upper upon the bottom of a shoe at the toe, having in combination, a tool for separating from the shoe the surplus material to be removed and means for positioning the bottom of a shoe at the toe constructed to permit the tool and toe part to be moved relatively to bring said tool and toe part into operative relation and arranged to control the position of the toe part in said relative movement and to maintain the shoe normally out of operative relation to the tool. 120 125

13. A toe trimming machine comprising a cutter arranged to permit manual presenta- 130

tion thereto of the toe part of a boot or shoe, and means movably arranged with relation to the cutter for positioning said toe part and constructed to control the position of said toe part in its presentation to the cutter and to move with the shoe into operative relation to the cutter.

14. A machine for reducing the projecting portions of an upper upon the bottom of a shoe at the toe having in combination a tool for separating from the shoe the surplus material to be removed and a gage having an acting part formed to project inwardly over the edge of the shoe and engage the bottom of the shoe at the toe and present the projecting portions of the upper to the tool said gage being constructed to permit adjustment in width of said acting part to receive shoes varying in size.

20 15. In a toe trimming machine, a rest arranged to receive against it the toe tip of a shoe and a gage having an acting part constructed to be engaged by the bottom of the shoe at the toe part and to project inwardly over the edge of the shoe, said gage being arranged to lie in effective relation to said toe part upon the positioning of the toe tip on the rest.

16. In a machine of the class described, a tool for separating from a shoe surplus material to be removed, a gage having an acting part arranged to be engaged by the toe part of the bottom of a shoe and to present the projecting portions of the upper to the tool, said gage being constructed to permit adjustment in width of said acting part, and a rest arranged to be engaged by the toe tip and adjustable in the direction of the length of the shoe with relation to the acting part of 40 said gage.

17. A machine for trimming the projecting portion of an upper from the bottom of a shoe at the toe, having, in combination, a cutter, a gage arranged for engagement with the bottom of a shoe and constructed to present the toe portion of the shoe in position to permit said portions of the upper to be trimmed by the cutter, and a rest to position the toe tip of the shoe, said gage and said rest 50 being constructed and arranged so that a shoe having its tip in position on the toe rest is prevented by the gage from being moved beyond a predetermined limit into the path of the cutter.

55 18. A machine for reducing the projecting portions of an upper upon the bottom of a shoe at the toe comprising a tool for separating

from the shoe the surplus material to be removed, said tool being arranged for continuous movement during its operation upon the shoe, and means for guiding the toe part of the shoe into the range of the tool in a path arranged to cause said portions to be removed by repeated movements of the tool longitudinal of the shoe in the direction of 65 the heel.

19. In a machine of the class described, a tool for separating from a shoe surplus material to be removed arranged to be continuously actuated, a gage having an acting portion shaped to receive the toe portion of a shoe, and a rest adjacent to said acting portion of the gage arranged to be engaged by the toe tip of the shoe, said cutter and gage and rest being relatively movable under the 75 pressure of the toe tip against the rest to permit a toe engaging said gage and rest to be brought into the path of the tool.

20. A machine for reducing the projecting portions of an upper upon the bottom of a shoe at the toe comprising a tool for separating from the shoe the surplus material to be removed, said tool being arranged for operation in a vertically curved path and means for presenting the toe part to the tool in position to cause said material to be removed by movement of the tool longitudinal of the shoe in the direction of the heel.

21. In a toe trimming machine, the combination with means for positioning the toe part of a shoe, of means for trimming projecting portions of the upper from said toe part by the separation from the shoe of successive layers of stock progressively from the toe tip toward the heel.

95 22. A machine for reducing the projecting portions of an upper upon the bottom of a shoe at the toe, having in combination, a rotary cutter for separating from the shoe the surplus material to be removed and a 100 gage formed to project inwardly over the edge of the shoe and present the projecting portions of the upper to the cutter simultaneously upon opposite sides of the toe part, said cutter and gage being arranged for relative adjustment to vary the depth of cut effected by the cutter.

In testimony whereof I have signed my name to this specification in the presence of two subscribing witnesses.

ORRELL ASHTON.

Witnesses:

WILHELMINA C. HEUSER,
EDITH C. HOLBROOK.

It is hereby certified that in Letters Patent No. 891,130, granted June 16, 1908, upon the application of Orrell Ashton, of Lawrence, Massachusetts, for an improvement in "Machines for Operating Upon the Toe Portions of Boots or Shoes," an error appears in the printed specification requiring correction, as follows: In line 62, page 2, the word "wheel" should read *heel*; and that the said Letters Patent should be read with this correction therein that the same may conform to the record of the case in the Patent Office.

Signed and sealed this 20th day of October, A. D., 1908.

[SEAL.]

C. C. BILLINGS,
Acting Commissioner of Patents.
